UNITED STATES PATENT OFFICE

168,229

AMUSEMENT GAME APPARATUS

Jerry C. Koci, Barrington, Ill., assignor to Chicago Coin Machine Co., Chicago, Ill., a corporation of Illinois

Application June 9, 1952, Serial No. 20,103

Term of patent 3½ years

(Cl. D34—5)

To all whom it may concern:

Be it known that I, Jerry C. Koci, a citizen of the United States of America and a resident of the village of Barrington, in the county of Lake and State of Illinois, have invented a new, original, and ornamental Design for an Amusement Game Apparatus, of which the following is a specification, reference being had to the accompanying drawings, forming a part thereof, and in which:

Fig. 1 is a perspective view of an amusement game apparatus showing my new design;

Fig. 2 is a top plan view of the same.

The drawing figures are lined to indicate transparency.

The back of the cabinet is plain, and both sides are substantially the same.

I claim:

The ornamental design for an amusement game apparatus, as shown and described.

JERRY C. KOCL.
